(57) **CLAIM**

The ornamental design for a table extender, as shown and described.

DESCRIPTION

FIG. 1 is a top rear perspective view of a table extender, showing our new design;

FIG. 2 is a bottom front perspective view thereof;

FIG. 3 is a top view thereof;

FIG. 4 is a bottom view thereof;

FIG. 5 is a left side view thereof;

FIG. 6 is a right side view thereof;

FIG. 7 is a front elevation view thereof; and,

FIG. 8 is a rear elevation view thereof.

The broken lines are included for the purpose of illustrating unclaimed portions of the table extender and form no part of the claimed design.

1 Claim, 8 Drawing Sheets
